COMBINED GUNREST, SEAT AND WALKING STICK

Rufus Norman, 7300 Cameron, Apt. 220,
North Little Rock, Ark. 72209

Filed Mar. 5, 1969, Ser. No. 16,043

Term of patent 14 years

Int. Cl. D3—03

U.S. Cl. D88—4

FIG. 1

FIG. 3

FIG. 1 is a perspective view of a combined gunrest, seat and walking stick shown in a seat-forming condition;

FIG. 2 is a front perspective view of FIG. 1 showing the device converted into a gunrest condition; and

FIG. 3 is a side elevational, perspective view showing the device converted into a cane.

I claim:

The ornamental design for a combined gunrest, seat and walking stick, as shown and described.
